PAIR OF EYEGLASSES

Jeannette Davis, 1211 Selby Ave., Los Angeles, Calif.

Filed Sept. 18, 1963, Ser. No. 76,631

Term of patent 14 years

(Cl. D57—1)

FIG. 1.

FIG. 2.

FIG. 3.

FIG. 4.

The front and opposite temple are shown broken away in FIGURES 3 and 4 for convenience of illustration.

The dominant features of my design reside in the portions shown in full lines.

I claim:

The ornamental design for a pair of eyeglasses, substantially as shown and described.
